UNITED STATES PATENT OFFICE.

EDWARD F. RAYMOND, OF SANTA FE SPRINGS, CALIFORNIA.

SIDE-TRACKING TOOL.

Application filed March 5, 1925. Serial No. 13,209.

To all whom it may concern:

Be it known that I, EDWARD F. RAYMOND, a citizen of the United States, and resident of Santa Fe Springs, in the county of Los Angeles, State of California, have invented new and useful Improvements in Side-Tracking Tools, of which the following is a specification.

This invention relates to a drilling tool especially serviceable in side tracking casting and tools lost in oil wells. Heretofore, ordinary drilling tools have been much used for this work, and in some instances, the drillers have made slight changes in the bits, these changes being matters of individual choice. Nearly all tools heretofore used for this purpose have been inefficient due to the friction encountered by rubbing against the casing. Difficulty has also been experienced in directing the tool around portions to be side tracked.

It is the primary object of this invention to provide a tool having a pilot for diverting the tool from the usual path. Another object of this invention is to provide a tool having a follower portion which will decrease the friction and act somewhat as a reamer. Another object of this invention is to provide a tool wherein the cutting parts can be easily replaced. Rollers are provided in the follower portion of the tool, and it is an object of this invention to provide novel means for mounting the rollers in position, for lubrication of the same and for the supply of circulation fluids to the cutters.

These objects together with other objects and corresponding accomplishments are obtained by means of the embodiment of my invention illustrated in the accompanying drawing, in which:

Fig. 1 is a side elevation, partly in section showing the complete tool; Fig. 2 is a section as seen on the line 2—2 of Fig. 1; Fig. 3 is a section as seen on the line 3—3 of Fig. 1; Fig. 4 is a fragmentary view showing a section of the tool as seen on the line 4—4 of Fig. 1; and Fig. 5 is a cap to permit removal and replacement of the cutter blades on the rollers.

Referring more particularly to the drawing, the tool comprises a follower body 6 having a threaded tapered pin 7 whereby it may be attached to the drill pipe or other means for rotating the tool. A peripheral recess extends about the body in which roll-

ers are inset. Extending axially through the body is a passage 9 having water courses 10 branching therefrom. There are, in the tool shown herein, four rollers mounted in 60 the recess 8.

The follower portion 6 of the tool is provided with a threaded socket to receive the pin of a pilot, the body of which is indicated by 11. The body is tapered, and 65 mounted upon the sides thereof are cutter blades 13. An opening or passage 14 communicates with passage 9 and has water courses 15 leading to the outside of the pilot body adjacent the tops of the blades 13. 70 The blades form the cutting portion of the pilot end of the tool, and in order to allow easy replacement thereof, the blades are formed separately and disposed in mortises in the body, being welded to each other and to the body below the line indicated by 17, thus making the tool integral at the tip 16. In order to replace blades, the pilot is removed and the tip 16 cut from the pilot body 75 above the line 17. The blades may then be driven out of the position in the body, and new blades may be substituted, the tips being welded together and dressed. The blades, 80 as will be noted, slant in respect to the axis of the tool.

The rollers in the follower comprise cylinders 18. Secured in each cylinder is a shaft 19. The shaft has a bore extending therethrough for the passage of lubricant. The ends of each shaft are journaled in bearings formed in the body and consisting of bores. The lower bore extends through the follower body and may be closed by a threaded plug 20. This construction permits the shaft 19 to be inserted into position through the lower bore. There are suitable bushings and washers provided for taking care of the wear. The upper bore or bearing has a duct 21 communicating therewith and opening through the top of the follower body.

This bore is arranged for the introduction of lubricant, which may be performed by any well known means such as a grease gun. Mounted in the cylinders are blades 22 set in dovetail recesses. The blades slant in the same direction as the blades 13 on the pilot body. In order to permit removal of the blades from the roller cylinder, without requiring removal of the cylinders, I have provided a cutaway portion on the follower body at the periphery best shown in Fig. 4 and indicated by 23. This cutaway portion

is so arranged that the inside of a blade 22 will clear the wall of the body, and the blades may be driven upwardly and out, as shown in Fig. 4. The cap 24 normally covers the cutaway portion, and is conveniently held in position by dovetails and tenons and screws.

In the operation of the tool, it is placed upon the drill pipe and used in the manner of an ordinary drilling tool. The pilot will cause the tool to be directed to one side of the portion of the hole which it is desired to pass. The tool follows the lead of the pilot, the rollers in the followers cutting and bringing the hole to the desired size without causing any undue friction.

What I claim is:

1. A tool of the character described comprising the combination of a tapered pilot body having mortises extending longitudinally, blades mounted in said mortises and welded to form an integral tip.

2. A tool of the character described comprising a tapered pilot body having longitudinally extending mortises, blades mounted in said mortises and welded to form an integral tip, and a follower portion having roller cutters mounted on the periphery thereof.

3. A tool of the character described comprising a tapered pilot body having longitudinally extending mortises, blades mounted in said mortises and welded to form an integral tip, and a follower body detachably secured thereto, said follower body having roller cutters inset in the periphery thereof and rotatable about axes extending longitudinally of said tool.

4. A tool of the character described comprising the combination of a tapered pilot body having longitudinally extending mortises, blades mounted in said mortises and welded to form an integral tip, and a follower portion secured to said pilot end having lateral cutters.

5. A tool of the character described comprising the combination of a tapered pilot end having lateral cutters extending longitudinally, and a follower head portion detachably secured thereto having a peripheral recess, rollers journalled in said recess upon axes extending longitudinally of said tool, said rollers having peripheral mortises, blades having tenons inset in said mortises so as to be removable endways from said rollers, the ends of said blades overlapping the wall of said recess, removable caps on

the periphery of said follower body whereby the ends of said roller blades may be cleared permitting removal of the latter.

6. A tool of the character described comprising the combination of a tapered pilot end having lateral cutters extending longitudinally thereof, a follower head portion having an annular peripheral recess, rollers journalled in said recess upon axes extending longitudinally of said tool, each of said rollers having peripheral mortises, blades having tenons inset in said mortises so as to be removable endways, the ends of said blades overlapping the upper wall of said recess, removable caps on the periphery of said follower head portion whereby the ends of said roller blades may be cleared permitting removal of the latter.

7. A tool of the character described comprising the combination of a tapered pilot end having lateral cutters extending longitudinally thereof, and a threaded pin at its large end, and a follower head having a socket to receive said pin and provided with an annular peripheral recess, rollers journalled in said recess upon axes extending longitudinally of said tool, each of said rollers having peripheral mortises, blades having tenons inset in said mortises, so as to be removable endways, the ends of said blades overlapping the upper wall of said recess, removable caps on the periphery of said follower head whereby the ends of said roller blades may be cleared permitting removal of the latter.

8. A tool of the character described comprising the combination of a tapered pilot body having longitudinally extending mortises, blades mounted in said mortises and welded to form an integral tip, a follower head detachably connected to said body, said follower head having an annular peripheral recess, rollers journalled in said recess upon axes extending longitudinally of said tool, each of said rollers having peripheral mortises, blades having tenons inset in said mortises so as to be removable endways, the ends of said blades overlapping the top wall of said recess, removable caps on the periphery of said follower head whereby the ends of said roller blades may be cleared permitting removal of the latter.

In witness that I claim the foregoing I have hereunto subscribed my name this 27th day of February 1925.

EDWARD F. RAYMOND.
